UNITED STATES PATENT OFFICE.

WILLIAM L. DENTON, OF RANDSBURG, CALIFORNIA.

ORTHOPEDIC APPARATUS.

Application filed May 14, 1924. Serial No. 713,214.

To all whom it may concern:

Be it known that I, WILLIAM L. DENTON, a citizen of the United States, residing at Randsburg, in the county of Kern and State 5 of California, have invented new and useful Improvements in Orthopedic Apparatus, of which the following is a specification.

My invention relates to orthopedic apparatus and consists of the novel features 10 herein shown, described and claimed.

The objects and advantages will appear from the drawings and specification.

The drawings illustrate the invention.

Figure 1 is a perspective showing an 15 orthopedic apparatus embodying the principles of my invention in use in connection with a hospital cot or the like and a Baltic frame, the operation shown being preliminary to the setting of a broken leg and applying the cast.

Fig. 2 is an enlarged detail plan of the stretching apparatus parts being shown in section.

Fig. 3 is a side elevation looking in the 25 direction indicated by the arrow 3 in Fig. 2.

Fig. 4 is a sectional detail on the line 4—4 of Fig. 3.

The details of the orthopedic device shown in the drawings are as follows:

30 The cot or bed 1 may be any of the ordinary constructions having a head frame 2 and a foot frame 3. The Baltic frame 4 may be of the ordinary construction having upper side bars 5 and 6 and is mounted upon the head and foot frames 2 and 3. Pulleys are connected to rings 9 and 10, said rings sliding upon the side bars 5 and 6 near the head of the bed 1. Ropes 11 and 12 run over the pulleys 7 and 8 and have blocks 40 13 and hooks 14, as required to form blocks and tackles, the free ends 15 of the ropes serving to operate the blocks and tackles. In a like manner, blocks and tackles 16 and 17 are mounted upon the rear ends of the 45 side bars 5 and 6.

The rectangular stretcher frame 18 is constructed of pipe and elbows and clips 19 are fixed upon the side bars of the stretcher 18 and have upwardly extending 50 ears to receive the hooks 14 of the blocks

and tackles so that by manipulating the ropes 15 the stretcher may be raised or lowered. A canvas 20 is stretched upon the frame 18 and has a central opening 21.

The folding and extensible shoulder support and head rest 22 is mounted upon the side bars of the shoulder frame 18 and may be elevated to support the shoulders and head of a patient.

Usually the patient having a broken leg 60 or the like is placed upon the portable stretcher 18 and brought to the bed. The leg stretcher and body support 34 is mounted upon the bed 1 and the details are as follows:

A board 35 rests upon the mattress and extends across the bed to prevent the frame from tipping. A block 36 is rigidly secured to the center of the board 35 and extends upwardly and has a flat upper face 37. A 70 flange base 38 rests upon the board 35 in front of the block 36 and is removably secured in place by bolts and wing nuts 39. A socket 40 extends upwardly from the base 38 and is internally screw threaded. The 75 removable post 41 is screwed down into the socket 40. A long sleeve 42 extends from the base 38 towards the foot of the bed and has a boss 43 carrying the thumb head set screw 44. The extension bar 45 is slidably mounted in the sleeve 42 and has depressions 46 to receive the point of the set screw 44 so that by loosening the set screw 44 the bar 45 may be adjusted inwardly or outwardly in the sleeve 42 and the set screw 80 44 tightened to hold the bar 45 from rotation and from endwise movement. An elbow 47 fits loosely upon the foot end of the bar 45 and is held removably in place by a pin 48. A second post 49 is fixed in the 85 elbow 47 and extends upwardly parallel with the post 41. A T 50 has its side opening 51, adapted to receive the upper end of the post 49 and the T is held securely in place by a pin 52, it being especially 90 important that the T 50 and the post 49 shall not rotate relative to the extension bar 45. Arms 53 and 54 are rigidly mounted in the ends of the T 50 and extend outwardly into the vertical planes containing 95 100

the sides of the frame 18. The adjustable heel clamps 55 and 56 are pivotally connected to set collars 55' and 56' slidingly and adjustably mounted upon the outer portions 5 of the arms 53 and 54. The pivotal connections consist of attaching plates 57 and 58 fitting upwardly against the set collars 55' and 56' and secured in place by pivots 59 and 60.

10 Bearing plates 61 and 62 extend downwardly from the forward ends of the attaching plates 57 and 58. Long adjusting screws 63 and 64 are mounted loosely through the bearing plates 61 and 62.

15 Crank handles 65 and 66 are formed integral with the outer ends of sleeves 67 and 68 and each sleeve 67 and 68 has a nut 69 at its forward end to work upon the screws 63 and 64 behind the bearing plates 61 and 20 62 so that by manipulating the hand cranks 65 and 66 the screws 63 and 64 may be operated to pass backwardly or forwardly through the bearing plates 61 and 62. Forks 70 and 71 are swiveled to the screws 25 63 and 64 by joints 70' and 71' and extend forwardly from the ends of the screws 63 and 64 and clamping screws 72 and 73 are mounted through the ends of the prongs of the fork 70 and have pads 74 and 75 upon 30 their inner ends. In a like manner, the fork 71 has clamping screws 76 and 77 mounted through the prongs of the fork 71 and pads 78 and 79 upon their inner ends.

35 Assuming that the patient has been brought in upon the portable stretcher 18, the patient and stretcher will be placed upon the bed 1, the blocks and tackles will be hooked to the clips 19 and the ropes 15 40 operated to raise the stretcher 18 and the patient a considerable distance above the bed 1 and then the board 35 will be placed across the bed with the block 36 extending upwardly. The post 41 will be placed into 45 the socket 40, the extension bar 45 will be adjusted approximately to the proper length, the hand cranks 65 and 66 will be operated to move the foot clamps forwardly, then the ropes 15 will be operated to lower 50 the stretcher 18 so that the post 41 and block 36 will pass upwardly through the opening 21 in the stretcher cover 20 and the block supporting face 37 will engage the lower end of the spine of the patient 55 and the post 41 will pass upwardly between the patient's legs and engage the pelvic bone at the upper end of the crotch. The feet will be placed in the foot clamps 55 and 56, the thumb screws 72 and 73 and 76 and 60 77 operated to grip the heels of the feet and the hand clamps 65 and 66 operated to pull upon the feet to pull the post 41 into the crotch and stretch the legs to the desired extent. The head and shoulders of 65 the patient will be raised at the proper

time and the support 22 elevated to support the head and shoulders, all as shown in Fig. 1. The blocks and tackles may be disconnected at any time during this operation.

70 If the patient's thigh bone is broken and the ends 80 and 81 overlapped the leg may be stretched and rotated and abducted or adducted to bring the ends 80 and 81 into line for setting, as shown in Fig. 1. Numerous other operations may be performed as required by the case.

75 The apparatus allows either internal or external rotation, and tensioning adducting and abducting. The desired position can 80 be maintained while a cast reaching from the axilla to and including the feet can be applied. Then the Bradford frame can be raised to support the body as the shoulder support is lowered, the crotch bar and heel clamps released, and the apparatus removed from under the Bradford frame and then the frame lowered to the bed so as not to disturb the cast while the plaster hardens. 85 The hole in the frame allows massage of the sacral region and the use of a bed pan by raising the frame by pulleys attached to the Baltic frame without disturbing the patient's position. The orthopedic apparatus rests on the bed and is prevented from 90 turning sideways by the transverse bar.

95 Various changes may be made without departing from the spirit of my invention as claimed.

100 I claim:

1. In an orthopedic device a leg stretcher and body support comprising a board adapted to rest crosswise upon a bed, a block extending upwardly from the board and adapted to support the lower end of a patient's spine, a removable post extending upwardly from the board beside the block, an adjustable extension bar extending horizontally from the board, a second post extending upwardly from the foot end of the extension bar, a cross bar at the upper end of the second post, supporting bearings pivotally connected to the ends of the cross bar, screws slidingly mounted through the bearings, hand cranks having nuts upon the screws behind the bearings, forks at the forward ends of the screws, clamping screws in the forks and adapted to engage a patient's feet so that when a patient is in position the legs may be stretched by operating the hand cranks.

110 2. In an orthopedic device a leg stretcher and body support comprising a board adapted to rest crosswise upon a bed, a block extending upwardly from the board and adapted to support the lower end of a patient's spine, a removable post extending upwardly from the board beside the block, an adjustable extension bar extending horizontally from the board, a second post ex- 115 120 125 130

tending upwardly from the foot end of the extension bar, a cross bar at the upper end of the second post, supporting bearings pivotally connected to the ends of the cross bar, screws slidingly mounted through the bearings, hand cranks having nuts upon the screws behind the bearings, forks swiveled at the forward ends of the screws, clamping screws in the forks and adapted to engage a patient's feet so that when a patient is 10 in position the legs may be stretched by operating the hand cranks so as to support a patient above the bed for tensioning, adducting, abducting and rotating the lower extremities and applying a cast. 15

In testimony whereof I have signed my name to this specification.

WILLIAM L. DENTON.
